Primary Examiner — Sandra L Morris(57) **CLAIM**

I claim the ornamental design for bendable plush toy, as shown and described.

DESCRIPTION

FIG. 1 is a front view of a bendable plush toy accordance with the new design.

FIG. 2 is a back view of the bendable plush toy of FIG. 1. FIG. 3 is a side view of the bendable plush toy of FIG. 1, in which the second side (not shown) is a mirror image hereof. FIG. 4 is a top view of the bendable plush toy of FIG. 1. FIG. 5 is a bottom view of the bendable plush toy of FIG. 1.

FIG. 6 is a front perspective view of the bendable plush toy of FIG. 1, depicting the toy bent into a first pose.

FIG. 7 is a front perspective view of the bendable plush toy of FIG. 1, depicting the toy bent into a second pose; and, FIG. 8 is a front perspective view of the bendable plush toy of FIG. 1, depicting the toy bent into a third pose.
